(57) **CLAIM**

The ornamental design for a planter box, as shown and described.

DESCRIPTION

FIG. 1 is a side and front perspective view including dip trays, showing our new design;

FIG. 2 is a perspective view without dip trays;

FIG. 3 is an opposite side, front and top perspective view of the design shown in FIG. 1;

FIG. 4 is a top plan view of the design shown in FIG. 1;

FIG. 5 is a bottom plan view of the design shown in FIG. 1;

FIG. 6 is a front elevational view of the design shown in FIG. 1;

FIG. 7 is a side view of the design shown in FIG. 1;

FIG. 8 is a side view of the design shown in FIG. 2;

FIG. 9 is an exploded, perspective view of a detail of the drip tray of the design shown in FIG. 1;

FIG. 10 is a perspective view of a detail of the watering cap of the design shown on the other side of FIG. 9;

FIG. 11 is an opposite side, front and top perspective view of the design shown in FIG. 2;

FIG. 12 is a bottom, side and front perspective view of the design shown in FIG. 1;

FIG. 13 is a bottom, side and front perspective view of the design shown in FIG. 2;

FIG. 14 is a top perspective view of the design shown in FIG. 1;

FIG. 15 is an inverted, perspective view of the design shown in FIG. 13;

FIG. 16 is an exploded, inverted, perspective view of the design shown in FIG. 15;

FIG. 17 is an exploded, inverted view of a detail of the design shown in FIG. 16;

FIG. 18 is a perspective view of the design shown in FIG. 2; and,

FIG. 19 is a perspective view of a detail of the design shown in FIG. 18.

The broken lines are included for the purpose of showing portions of the planter box that form no part of the claimed design.

1 Claim, 18 Drawing Sheets
